UNITED STATES PATENT OFFICE.

RUDOLF LOEB, OF CAMDEN, NEW JERSEY.

PROCESS OF FORMING EMBROIDERY-STITCHES.

1,086,190.

Specification of Letters Patent. Patented Feb. 3, 1914.

Application filed September 7, 1911. Serial No. 648,093.

To all whom it may concern:

Be it known that I, RUDOLF LOEB, a citizen of the United States, and a resident of Camden, Camden county, New Jersey, have 5 invented an Improved Process of Forming Embroidery-Stitches, of which the following is a specification.

My invention relates to embroidery or the formation of raised stitches upon fabric 10 for the purpose of displaying thereon a design of a predetermined character, and my invention consists of an improved process of effecting the application of such stitches to the fabric to define the desired design. This 15 object and other details of my invention are more fully described hereinafter, reference being had to the accompanying drawings illustrating diagrammatically the features of my invention, in which:

20 Figure 1, is a view showing one form of stitch made in accordance with the process forming the subject of my invention; Figs. 2 and 3, are views illustrating other stitches, and Fig. 4, is a view of the under side of 25 the fabric illustrating the loops of the stitches shown in Fig. 1.

In the process of forming this improved embroidery, I employ a machine having a 30 needle mounted to vibrate; the movement of which regulates the length of the stitches, and in the operation of the machine carrying such needle provision may be made for regulating the extent of vibration to determine the length of such stitches.

35 In operation, the needle is vibrated back and forth toward the operator, and the stitches may be laid very close together or wide apart, as the character of design may suggest or require, and such disposal of the 40 stitches is effected by the operator moving the fabric; the needle vibrating in a single plane. The fabric is moved laterally with respect to the movement of the needle, although such movement may be accompanied by a movement almost in line with the 45 movement of the vibrating needle. The resultant of these two movements is indicated by the stitches formed, which are laid or disposed diagonally with respect to the general direction of that portion of the design 50 filled by the same.

In their formation, the stitches 2 and 3 may be laid in two substantially paralleling

rows; the stitches 2 being disposed at an angle with respect to the stitches 3 and the 55 general direction of that portion of the design covered by the same. The embroidery may be of the character illustrated in Fig. 1, in which the respective sets of stitches are in substantial parallelism and in which the 60 narrowing of the embroidery portion formed by the raised stitches to follow the contour of the design is effected by moving the fabric without shortening the stitches 2. In the formation of a thin line, therefore, the 65 stitches lie diagonally with respect to such line, and in general their position is diagonal with respect to the general line of direction of the figures formed by the design. In addition to this formation of the stitches, 70 they may be formed short and long by giving the needle a short and long movement of vibration, as shown in Fig. 2. In other instances the vibration of the needle may be graduated during the formation of the 75 stitches to produce automatically gradually lengthened stitches and gradually shortened stitches as may be desired in the covering of the design, as shown in Fig. 3. On the under side of the fabric the loops of the 80 stitches are caught by a shuttle thread.

In Fig. 1 of the drawings, 1 represents the fabric, 2 one set of paralleling stitches, 3 the other set of paralleling stitches. In Fig. 2, the long stitches are indicated at 2, 85 and the short stitches at 2^a. In Fig. 3, the stitches are indicated at 2^b. In all instances the stitches form loops 4 on the under side of the fabric, such as indicated in Fig. 4; a shuttle thread 5 engaging such loops. 90

I claim:

1. The process of embroidering, which consists in laying, by a thread-carrying implement vibrating in a fixed path, a plurality of sets of stitches upon a suitable fabric, 95 the stitches of the respective sets substantially paralleling each other, and manually moving the fabric in any desired direction with respect to the said vibrating thread-carrying implement.

2. The process of embroidering, which consists in laying, by a thread-carrying implement laterally vibrating in a fixed path, a plurality of sets of stitches diagonally with respect to each other upon a suitable 105 fabric, the stitches of the respective sets

substantially paralleling each other, and manually moving the fabric in any desired direction with respect to the said laterally vibrating thread-carrying implement to follow and form the contour of an embroidered design.

In testimony whereof, I have signed my

name to this specification, in the presence of two subscribing witnesses.

RUDOLF LOEB.
